UNITED STATES PATENT OFFICE.

FREEBORN F. RAYMOND, 2d, OF NEWTON, MASSACHUSETTS.

HEEL-NAILING MACHINE.

SPECIFICATION forming part of Letters Patent No. 316,827, dated April 28, 1885.

Application filed January 20, 1885. (No model.)

To all whom it may concern:

Be it known that I, FREEBORN F. RAYMOND, 2d, of Newton, in the county of Middlesex and State of Massachusetts, a citizen of the United States, have invented a new and useful Improvement in Heel-Attaching Machines, of which the following is a full, clear, and exact description, reference being had to the accompanying drawings, forming a part of this specification, in explaining its nature, in which—

Figure 1 is a vertical central section of a machine containing the features of my invention. Fig. 2 is a plan view thereof. Fig. 3 is a view in vertical section of a portion of the templet or pressure plate and yielding templet-block and a heel-blank. Fig. 4 represents a section showing the same parts, and also the awls and awl-holder, the yielding templet-block having been moved down and latched to clamp the heel-blank upon the heel-support. Fig. 5 represents in vertical section the same parts shown in Fig. 3, with the drivers and driver-block in position, showing the manner of releasing the devices which hold or lock down the yielding templet-blocks. Fig. 6 is a view, part in front elevation and part in vertical section, of my machine. Fig. 7 represents in vertical section a templet-block and a top-lift-holding device or plate.

The invention is an improvement upon that described in my application for Letters Patent of the United States, filed January 20, 1885, Serial No. 153,388. It embraces a construction whereby three or more jacks or heel-supports are fed in succession to the pricking, driving, and spanking devices, whereby the pricking of one heel, the attaching of another, and the spanking of still another are simultaneously performed. It still further relates to various details of construction, all of which will hereinafter be fully described.

A represents the central post or column, which is attached or bolted to the bed a. Upon this column is arranged, so as to slide thereon, the head B, which is shaped in plan substantially as shown in Fig. 2, and it supports a group of awls, b, a group of drivers, b', and the spanker-block b², all in operative position—that is, so placed upon the head that upon its reciprocation they are in a position to operate simultaneously. The head is re-

ciprocated by the rod b³, link b⁴, and crank b⁵ on the shaft b⁶, upon which is the driven pulley, or which is revolved by the pulley-shaft 55 through connecting-gears.

The templet or pressure plate C is adapted to have a vertical movement, and also a revolving movement. It is moved vertically by means of the presser-block o, which is attached to the cross-head B in the manner specified in my said application; but it does not continue entirely around the column, there being space left for the attachment to the column of a lever, hereinafter referred to. The templet supports a series of yielding templet-blocks, c, one for each jack or work-support. These templet-blocks have a yielding movement in the templet-plate, in order that they may be used to clamp the heel-blank upon the boot or shoe sole, and hold it clamped while it is being pricked and while it is being transferred from the pricking to the driving devices, and while the attaching-nails are being driven. Each block c is arranged to fit into a hole made in the templet-plate, and they are supported therein by the springs c', which surround the guide-posts c², and they are held locked down by the automatic latches c³, which are pivoted at each side of the block c⁴ to the 75 templet or pressure plate in a recess cut therein, and are by the springs c⁵, upon the downward movement of the templet-block, moved upon the edge thereof to hold the same down. The latches c³ also prevent the springs c' from 85 forcing the templet-blocks upward too far by engaging automatically with the notches c⁶ cut in the side thereof, as shown in Figs. 3, 4, and 5.

D are the jacks, and they are arranged to slide upon the revolving table E, as described 90 in my said application. The table is adapted to be revolved on the column, and it has a sleeve, e, which connects with a sleeve, c⁷, extending down from the templet or pressure plate. The templet or pressure plate of course has a vertical movement in relation to the sleeve e, and it is lifted by the cross-piece c⁸ on the reciprocating rod b³, as described in my said application. The templet or pressure plates are automatically locked in position by a spring-bolt 100 or other device, as described in my said application, and the jacks may be automatically moved into and out of operation by the device described in my said application, or by the

device described in an application of even date herewith.

In operation the boy or attendant places the boot or shoe upon the work-support; and, 5 if he also locates the heel-blank, puts it in proper position, and he, by means of the lever F, which is pivoted to the column at f, and which has a pressure or bearing block, f², which is, by the movement of the lever, 10 moved or pressed downward to move the templet-block c upon the heel-blank, clamps it firmly to the boot or shoe. The table is then revolved, bringing another jack before him, and the operation of placing the boot or shoe 15 upon the jack or heel-support and clamping the heel thereon is continued. Meanwhile the first jack with the heel clamped thereon has been advanced to a position under the awls, and the machine then makes a reciprocation and the heels are pricked or formed in the heel-blank. Upon the next movement of the revolving table E, the first heel-blank thus pricked is advanced to a position beneath the driving devices, and another or second 20 heel is brought into position beneath the awls, a second reciprocation of the machine forms the holes in the second heel and drives the nails, which have previously been fed into the templet-block, into the first heel, and 25 attaches it to the sole or soles of the boot or shoe, and another movement of the revolving table brings the first heel, which is now attached, under the heel-spanker, the second heel, which has been pricked, under the nail- 30 ing devices, and a third heel under the awls. If the heel is to be blind-nailed, the top lift is 35 then fed into position beneath the templet-block by the movement of the top-lift plate, so that the top lift is properly located, and a 40 third reciprocation of the machine causes the heels to be formed or pricked in one heel-blank, the nails to be driven through another heel-blank, and a top lift to be spanked upon another heel-blank, and the operation thus 45 continues in this manner, each reciprocation of the head applying a top lift to one heel, driving the attaching-nails of another, and forming the holes in another. Upon the downward movement of the drivers, the latches c³ 50 on the templet-block are moved back automatically by contact of the edge or lower corner of the block with the inclined surfaces of the latches, (see Fig. 5,) so that upon the upward movement of the drivers and driver-block the templet-block follows immediately thereafter, and also the templet-plate, and the templet-block lifts with the driver-block, 55 so that the latches cannot engage with its upper surface. This enables the top-lift plate to be moved with the top lift into position 60 and renders the hand-unlatching of the templet-block unnecessary. Each yielding templet-block c is provided with a top-lift plate, G, which slides in a dovetail recess formed 65 therein. One portion of this plate forms a templet and another portion carries the clamps or jaws for holding the top lift. The portion

which forms the templet should project below the portion carrying the top-lift holder, and it may be at one end or the other of the plate, 70 as desired. It is preferable, however, that the top-lift holder be at the inner end of the plate, in order that the plates may be pushed away in while the templet or pressure plate C is being revolved, until it becomes unnecessary to locate or bring into position the top lift over the heel-blank. It will be observed that by this construction the operations of 75 pricking, driving attaching-nails, and spanking are carried on simultaneously in different 80 holes, that the heel and work can be transferred accurately from the pricking devices to the driving devices, and that the top lift can be easily applied.

For feeding the templets with nails I may 85 use a nail-carrier, such as is described in a pending application, or I may use a separate or detachable nail-holder adapted to be filled and to be moved over the holes in the templet and to then deposit the nails therein. 90

It may not always be desirable for the attendant to locate the heel-blank, and when he does not it is done by the operator, who places it in position upon the sole of the boot or shoe after it has been moved into position beneath the awls, and in that case the downward movement of the awl-block automatically locks the templet-block down upon the heel-blank, so that the heel remains clamped in position until it is released automatically by the driver-block, as herein specified. The lever F is held up by means of the spring f. Of course I may use, in connection with each jack or heel-support, any of the shoe-centering devices or heel centering and holding appliances described in the various Henderson and also in my patents and applications. 100 105 110 115 120 125 130 135

In Fig. 7 the top-lift-holder plate and spanker-plate G is represented as locked in place, so that the holes in the part which forms a portion of the templet register with the holes in the remainder of the templet. The locking device comprises a spring-operated bolt or latch, g, which automatically enters either the templet registering-hole g' or 115 the top-lift and spanker registering-hole g². Of course, this sliding templet, top-lift, and spanker plate may be used in connection with any templet-block through which nails are driven or from which expelled, and whether 120 in the position shown in the drawings—that is, beneath the templet—or inverted and on top of it.

Having thus fully described my invention, I claim and desire to secure by Letters Patent of 125 the United States—

1. In a heel-attaching machine, the combination of a series of jacks or heel-supports, a templet or pressure plate, a reciprocating head carrying a gang of awls, a gang of drivers, a top-liftattaching or spanking device, and mechanism, substantially as described, to bring three of said jacks simultaneously into operative position, whereby, upon one reciproca-

- tion of the cross-head, one heel is pricked, another heel attached to the boot or shoe, and the third heel spanked, all substantially as set forth.
5. 2. In a heel-nailing machine, a templet or pressure plate having a yielding templet-block and a locking device for locking the block upon the heel-blank, all substantially as and for the purposes described.
10. 3. In a heel-nailing machine, the combination of the templet or pressure plate, a yielding templet-block, a locking device for locking it down upon the heel-blank, and a presser-block, f^2 , for moving it, all substantially as and for the purposes described.
15. 4. In a heel-nailing-machine, the templet or pressure plate C, having a series of movable templet-blocks, each of which is adapted to be moved vertically in relation to the templet or pressure plate and to be locked in its lowest position, all substantially as and for the purposes described.
20. 5. In a heel-nailing machine, the combination of the templet or pressure plate, a series of yielding templet or clamping blocks carried thereby, and a series of sliding plates supported by said templet or clamping blocks, each of which forms a portion of a templet, a top-lift spanker, and a support for top-lift-holding device or top-lift-holding devices, all substantially as and for the purposes described.
25. 6. In a heel-nailing machine, the combination, in a heel-attaching machine, of a series of jacks or heel-supports, a series of templet or clamping blocks adapted to be moved down upon the heel-blanks and to be automatically locked thereon, and the reciprocating head B, supporting the awls, drivers, and pressure-block b^2 in a position to operate simultaneously upon three different heels, all substantially as and for the purposes described.
30. 7. In a heel-nailing machine, the combination, in a heel-attaching machine, of a vertically-movable templet or pressure plate, C, supporting a series of templet-blocks, c , which are vertically movable in relation to the templet-plate, all substantially as and for the purposes described.
35. 8. In a heel-nailing machine, the combination, in a heel-attaching machine, of the reciprocating pressure-block b^2 , the templet-block c , vertically movable, and the templet and spanker plate G, horizontally movable in the templet-block, all substantially as and for the purposes described.
40. 9. In a heel-nailing machine, the combination of a jack or heel-support, a templet or clamping block adapted to be automatically locked down upon the heel, and the reciprocating block for automatically unlocking the templet-block, all substantially as and for the purposes described.
45. 10. In a heel-nailing machine, the combination of a jack or heel-support, a templet-block, and a lock for locking the same upon the heel-blank, a reciprocating driver-block carrying an unlatching device for automatically unlatching or unlocking the templet, and a transerrer or carrier for transferring the templet, the heel, and jack to a position under the pressure-block, all substantially as and for the purposes described.
50. 11. In a heel-nailing machine, the combination of the templet or pressure plate C, the templet c , the posts or studs c^2 , and the springs c' , all substantially as and for the purposes described.
55. 12. In a heel-nailing machine, the combination of the pressure or templet plate C and the latches or locks c^3 , all substantially as and for the purposes described.
60. 13. In a heel-nailing machine, the combination of the templet or pressure plate C, the templet-block c , having the notches c^4 , and the automatic latches or locks c^3 , adapted to engage with the notches, as and for the purposes described.
65. 14. In a heel-nailing machine, the combination of the templet-block c , the sliding templet, and top-lift-holding device or spanker, and a lock or latch for automatically locking the sliding plate in operative position either as part of the templet or as a top-lift attaching or spanking device, all substantially as and for the purposes described.
70. 15. In a heel-nailing machine, the combination of the templet-plate C, the plate G, having the register-holes g^1 g^2 , and the lock or latch g , all substantially as and for the purposes described.
